UNITED STATES PATENT OFFICE

2,522,933

TRIP MOVEMENT FOR WATCHMEN'S
PATROL BOXES

Ernest C. Engelmann, Arlington, Va.

Application July 28, 1949, Serial No. 107,355

2 Claims. (Cl. 74—526)

(Granted under the act of March 3, 1883, as
amended April 30, 1928; 370 O. G. 757)

1

The invention described herein may be manufactured and used by or for the Government of the United States for governmental purposes without payment to me of any royalty thereon in accordance with the provisions of the act of April 30, 1928 (ch. 460, 45 Stat. L. 467).

The invention relates to a device for use with the present key operated movement on night watch patrol boxes, and particularly to a collar and stop plate which protects the mechanism against damage which may result from the use of excessive force in turning the guard's key.

In the accompanying drawing which illustrates a preferred form of my invention:

Figure 1 is a side elevation showing a mechanism for tripping an electric switch by means of a manually operated key including the applicant's novel collar and stop plate.

Figure 2 is a side elevation showing the applicant's novel collar and stop plate turned by a key (not shown) to registering position.

Figure 3 is a section on the line 3—3 of Figure 1.

In these drawings, 10 represents a key stem provided with a transverse hole for a pin 11 adapted to trip a lever 12 which in turn serves as a means for tripping an electric switch in a signaling circuit (not shown). The key stem is provided with a squared end 13 which is adapted to be operatively connected with a watchman's key having a coacting recess. My novel collar 14 is provided while a stop plate 15 integral with the collar 14 has apertures for the pin 11, with an arcuate slot 16 for a stop pin 17 of the original device and with a hole adjacent its outer end for receiving a coiled tension spring 18 of the original device.

The applicant's attachment involves no major alterations of the present design, not illustrated, it being necessary merely to pull the original pin 11 out of the stem 10, slip the collar 14 over the stem 10 with the transverse apertures in alignment with the hole in the stem 10 and the stop pin 17 in the arcuate slot 16 thread the pin 11 through the stem 10 and collar 14, then attach the tension spring 18 to the stop plate 15 instead of the pin 11. It may be necessary to cut off an excess of the original pin 11 when altering the original movement by the combination with the novel collar and stop plate.

Force applied by the watchman through his key to the squared end 13 of the stem 10 is transmitted as a shearing force to the applicant's collar 14 through the oppositely extending parts of the pin 11 to the wide stop plate 15 to the original

2

stop pin 17. With the present design (not illustrated), the application by a watchman of excessive force through his key causes that part of the present longer pin 11 which engages the stop pin 17 to either bend or break, thereby disconnecting the spring 18 from the originally longer pin 11 so that the switch is no longer returned to its initial position after each key operation. The applicant substitutes for a portion of the original pin 11 the stop plate which is sufficiently wide in a plane perpendicular to the axis of the key stem 10 to provide ample strength to resist any stress which may be applied through a watchman's key.

15 It should be understood that the present disclosure is for the purpose of illustration only, and that the invention includes all modifications and equivalents which fall within the scope of the appended claims.

What is claimed is:

1. In a night watch patrol box provided with a key operated tripping mechanism the improvement which comprises a key stem enclosing collar provided with two transverse apertures which are aligned with a transverse aperture in said stem, a stop plate integral with said collar and provided with an arcuate slot for a stop pin and an aperture for attaching a tension spring, whereby said mechanism is protected against damage due to excessive force applied by a key to said stem.

2. In a patrol box provided with a key operated circuit making and breaking mechanism, the improvement which comprises an enclosing collar for a transversely apertured key stem said collar being provided with two aligned transverse apertures for receiving a pin, a stop plate integral with said collar which provides two limiting stops for a stop pin and means for attaching a tension spring.

ERNEST C. ENGELMANN.
